United States Patent Office

Des. 193,684
Patented Sept. 25, 1962

193,684

EXPANDED METAL SHEET

William M. Ries, Wheeling, W. Va., assignor to Wheeling Steel Corporation, Wheeling, W. Va., a corporation of Delaware

Filed Mar. 17, 1961, Ser. No. 64,356

Term of patent 14 years

(Cl. D54—2)

FIGURE 1 is a plan view of an expanded metal sheet embodying my new design; and

FIGURE 2 is a cross-sectional view of the expanded metal sheet shown in FIGURE 1, taken on the line 2—2 of FIGURE 1.

FIG. 3 is an enlarged fragmentary view of a portion of the sheet.

I claim:

The ornamental design for an expanded metal sheet, as shown.
